HIS ATTORNEY

thence upwardly through the interior of one of the arms 36 to a supporting pin 78 provided on the arm 36. The capillary tube from this point extends alongside the round end portion 42 of the heater 40 and is supported by the bracket 72 welded to the terminal portion 42 adjacent the hinge 46. This portion of the capillary tube 64 is substantially parallel to the axis of the end portion 42.

The capillary tube 64 extends beneath the range top 20 to a diaphragm operated switch means 74 which includes a metal bellows 76 operating a switch mechanism 78 connecting with a supply conductor 89 and a conductor 82 connecting with the terminal 44 for the heater 40. The opening and closing temperatures of the switch means 78 are controlled by a temperature adjusting knob 84 to control the connection and disconnection of the heater 40 to and from the power line 80 in accordance with the temperature of the thermostat bulb 54 adapted to be held against the bottom of a vessel upon the heater 40. The heater 40 may include heating circuits 86 and 88 connecting with conductors 90 and 92 each provided with individual switch means connecting with a 117 volt supply conductor 94 and a 235 volt supply conductor 96. These different connections make it possible to provide different heating rates for the surface heater 40 in addition to the thermostat control provided by the thermostat bulb 54, the capillary tube 64 and the diaphragm operated switch 74.

The arrangement of the capillary tube parallel to the end portion 42 of the heater makes it possible to readily clean the heater merely by tilting the heater 40 upwardly on its hinge connection 46. This raises the support 36 with it so that the drip pan 30 may be removed for cleaning and the trim ring 24 is made accessible for cleaning without removal.

A modified form of the invention is shown in Figures 4 to 6. In this form there is provided a combined trim ring and drip pan 130 provided with a continuous seamless integral rim 124 which has a sufficiently wide flange to overlap the portion of the range top 120 surrounding the surface heater unit opening 121. The top is provided with a step-down flange 122 immediately surrounding the aperture 121 for receiving the bowl-shaped portion of the drip pan 130. This drip pan 130 is provided with a raised central outlet portion 132. The flange portion 122 includes two arcuate segments upon which rest the shoulders 145 and 147 of the pan 130.

Two arms 149 and 151 of the three-armed support 136 rest upon the shoulders 147 and 145 as shown in Figures 4 and 5. The three-armed support 136 is formed of sheet metal and the arms are shaped in the form of an inverted U to provide stiffness. The support 136 includes a raised central portion 138 having a centrally located aperture through which projects the thermostat bulb 54. As shown in Figures 1 to 3 the central portion is provided with a spring cage 166 having its upper flanges riveted to the central portion 54. A compression type coil spring 168 resiliently urges the bulb 54 upwardly into engagement with the bottom of the cooking vessel. The bulb 54 is connected by a capillary tube 164 to a switch arrangement similar to the switch arrangement 74 in Figure 2. The capillary tube is connected to a diaphragm operated switch means which is connected in series with the surface heater 140 as is shown in Figure 2.

The third arm 135 of the heater 140 is supported by a bracket 137 fastened to the flange 122 by a screw 139. This bracket 137 projects within the arm 135 as shown in Figures 4 and 6. The arm 135 is loosely connected to the bracket 137 by an inverted T-shaped connector 165 which extends upwardly through adjacent slots in the support 137 and the arm 135 and is provided with a cotter pin extending through its aperture above the support 136 to provide a loose pivotal connection. The support 136 supports a tubular sheathed type of surface heater 140 arranged in a flat spiral and shaped similarly to the heater 140 in Figures 1 to 3. This heater is preferably pro-

vided with a hinge support similar to the hinge connection 46 shown in Figures 1 to 3. The connector 165 is provided with a loop at the bottom through which extends the capillary tube 164.

This supports the intermediate portion of the tube 164 and limits its bending stresses. The connector 165 prevents the removal of the support 136 and also limits its movement so that the bending of the capillary tube 164 is greatly reduced. To remove the combined drip pan and trim ring 130 there is provided an aperture 141 in the vertical side wall of the drip pan 130 on either side of and below the connector 165. This aperture is entirely below the rim 124. To remove the drip pan 130 the drip pan is lifted and then pulled directly away from the bracket 137 and the pan 130 is pulled away from the bracket 137 allowing the pan 124 to be removed with the surface heater 140 and its bracket 136 passing through the aperture 141 as the pan 130 is being pulled upwardly and away from the bracket 137. The pan 130 can then readily be taken to a suitable sink for cleaning and can be readily replaced following cleaning by passing the heater 140 and its support 136 again through the aperture 141 until it fits in place in the aperture 121 in the range top 120 as shown in Figures 4 to 6. This arrangement insures that the housewife will not get her hands in the vicinity of the terminals of the heaters and also limits the bending upon the capillary tube 164. This provides a simple arrangement.

The weight of any cooking utensil upon the surface heater 140 will be transmitted through the three-armed support 136 to the shoulders 145 and 147 to the flange 122 of the range top 120. The bulb 54 will be pressed against the bottom of such a surface vessel by the spring 168. The expansion of the liquid in the bulb 154 will be sufficient when the proper temperature in the surface vessel is reached to operate the diaphragm operated switch under open position to discontinue the flow of current through the heater 140. This arrangement is also excellent in appearance and very convenient.

In accordance with the provisions of Rule 78a, reference is made to the following prior filed applications: S. N. 344,867 filed March 26, 1953, now Patent 2,754,403 issued July 10, 1956, and S. N. 368,895 filed July 20, 1953, now Patent 2,754,405 issued July 10, 1956.

While the form of embodiment of the invention as herein disclosed constitutes a preferred form, it is to be understood that other forms might be adopted, as may come within the scope of the claims which follow.

What is claimed is as follows:

1. An electric range including a top provided with a surface heater opening, a removable drip pan provided with an integral continuous uninterrupted rim extending over the portions of said top bordering said opening, an electric surface heater within said drip pan, said pan having an elongated horizontal opening beneath the rim large enough to pass said heater through it, said heater having its terminal portion extending through said opening, a pivotal connection between said heater and said range top extending through said opening, a resiliently mounted thermostat bulb within said heater, a diaphragm operated switch means associated with said top, for controlling said heater, and a capillary tube extending from said bulb through said opening to said diaphragm operated switch means.
2. An electric range including a top provided with a surface heater opening, a removable drip pan provided with an integral continuous uninterrupted rim extending over the portions of said top bordering said opening, an electric surface heater within said drip pan, a support beneath said heater within said drip pan, said pan having an elongated horizontal opening beneath the rim large enough to pass said heater and support through it, a pivotal connection between said top and said support passing through said opening, a thermostat bulb resiliently mounted upon said support within said heater, a

diaphragm operated switch means associated with said range top, for controlling said heater, a capillary tube extending from said bulb through said opening to said diaphragm operated switch means.

3. An electric range including a top provided with a surface heater opening, a removable drip pan provided with an integral continuous uninterrupted rim extending over the portions of said top bordering said opening, an electric surface heater within said drip pan, a support beneath said heater within said drip pan, said pan having an elongated horizontal opening beneath the rim large enough to pass said heater and support through it, said support including an endless loop surrounding an opening and arms extending outwardly from said loop, one of said arms being provided with a slot, said range top including a projection extending adjacent said slot, and a loose coupling extending from said projection through said slot.

4. An electric range including a top provided with a surface heater opening, a removable drip pan provided with an integral continuous uninterrupted rim extending over the portions of said top bordering said opening, an electric surface heater within said drip pan, a support beneath said heater within said drip pan, said pan having an elongated horizontal opening beneath the rim large enough to pass said heater and support through it, said support including an endless loop surrounding an opening and arms extending outwardly from said loop, one of said arms being provided with a slot, said range top including a projection extending adjacent said slot, and a loose coupling extending from said projection through said slot, a thermostat bulb resiliently mounted within said opening surrounded by said loop, a diaphragm operated switch means associated with said range top for controlling said heater, and a capillary tube connecting said bulb and said diaphragm operated switch means, said capillary tube having an intermediate portion extending along the arm provided with said slot.

5. An electric range including a top provided with a surface heater opening, a removable drip pan provided with an integral continuous uninterrupted rim extending over the portions of said top bordering said opening, an electric surface heater within said drip pan, a support beneath said heater within said drip pan, said pan having

an elongated horizontal opening beneath the rim large enough to pass said heater and support through it, said support including an endless loop surrounding an opening and arms extending outwardly from said loop, one of said arms being provided with a slot, said range top including a projection extending adjacent said slot, and a loose coupling extending from said projection through said slot, a thermostat bulb resiliently mounted within said opening surrounded by said loop, a diaphragm operated switch means associated with said range top for controlling said heater, and a capillary tube connecting said bulb and said diaphragm operated switch means, said capillary tube having an intermediate portion extending along the arm provided with said slot and having a portion supported by said loose coupling.

6. An electric range including a top provided with a surface heater opening, an electric surface heater disposed in said opening, said top being provided with mounting means for pivotally supporting said surface heater for pivoting about a given axis, a thermostatic bulb resiliently mounted within said surface heater for pivotal movement with said heater, said bulb having a surface for engaging the bottom of a utensil resting on said heater, a stationarily mounted diaphragm operated switch means associated with said range top for controlling said surface heater, and a capillary tube having one end communicating with the interior of said thermostatic bulb and having an intermediate portion with its longitudinal axis extending along and substantially parallel to said given axis for a substantial distance and connecting at its opposite end to said diaphragm operated switch means whereby upon pivotal movement of said surface heater and said bulb relative to said top and switch means said intermediate portion of said capillary tube is twisted in torsion about its longitudinal axis.
